UNITED STATES PATENT OFFICE.

WILLIAM N. BEST, OF BROOKLYN, NEW YORK.

SYSTEM FOR SUPPLYING LIQUID FUEL TO BURNERS.

1,357,309.

Specification of Letters Patent.

Patented Nov. 2, 1920.

Application filed March 6, 1920. Serial No. 363,725.

To all whom it may concern:

Be it known that I, WILLIAM N. BEST, a citizen of the United States, and a resident of Brooklyn, in the county of Kings 5 and State of New York, have invented certain new and useful Improvements in Systems for Supplying Liquid Fuel to Burners, of which the following is a specification.

10 This invention is an improved system for supplying liquid fuel to burners and is intended primarily for viscous oils or other fluid fuels which, by reason of high viscosity, do not flow freely through the supply pipes at atmospheric temperature or at the particular temperature at which the fuel is or may be stored. The liquid fuel is burned to heat a low pressure steam boiler and, as an important feature of my 15 invention, I maintain a circulation of the boiler water, heated by the burning fuel, in heat interchanging relationship with the tank supplying fuel to the burner of the boiler. Thus a portion of the heat of the 20 burning fuel is utilized for maintaining the fuel in such condition that it may be conveniently delivered to the burner.

25 As a further feature I maintain a continuous circulation of the fuel as well as of the boiler water, utilizing a single source of power for maintaining both circulations.

30 In the accompanying drawings I have illustrated, somewhat diagrammatically, one form of apparatus which may be utilized 35 for carrying out my invention but obviously I do not care to be limited to this specific construction.

35 In these drawings:

40 Figure 1 is a top plan view; and Fig. 2 is a side elevation.

45 I have illustrated my invention in connection with a low pressure steam boiler 10 of any suitable construction and having a fire chamber 11. The details of the boiler have 50 not been illustrated as they form no portion of my invention. For heating the boiler I have illustrated, somewhat diagrammatically, a burner 12 which has a liquid fuel supply pipe 13 and a compressed 55 air supply pipe 14 connected thereto. The burner has outlets so juxtaposed that the compressed air escapes across the fuel outlet and delivers a spray of the fuel into the combustion chamber. The burner itself 60 forms no portion of my present invention,

but may be constructed as illustrated in my prior Patents 708,453 issued September 2, 1902 and 752,195 issued February 16, 1904. The liquid fuel may be stored in any suitable receptacle at the proper distance from 60 the burner. I have illustrated a tank 15.

In carrying out my invention I provide the tank with steam passages in heat interchanging relation thereto. I have illustrated a hot water coil 16 having one end 65 connected to the boiler below the water line thereof by a pipe 17 and the other end also connected to the boiler below the water line by a pipe 18. In one of these pipes, preferably the pipe 18 leading from 70 the boiler to the coil, I insert a suitable water circulating pump 19. This is of rotary form and may be of any suitable type. The pump serves to continuously withdraw water from the boiler, circulate it 75 through the heating coil 16 and return it to the boiler through pipe 17.

The oil is withdrawn from the tank by a pipe 20 and delivered by a rotary pump 21 through a pipe 22 and back to the tank 80 through a pipe 23. The pipe 13 delivering oil directly to the burner, communicates with the pipe 22 and there is preferably a pressure relief valve 24 at or adjacent to this point. The pump 21 thus continuously circulates oil and the burner is supplied with 85 oil under comparatively low pressure from this circulating pipe. Obviously there may be any desired number of burners with corresponding branch pipes 13 from the oil 90 circulating system. Where the system is used with a boiler producing low pressure steam, the vaporizing or spraying of the oil is preferably accomplished by a pressure blower 25 which may also be of a rotary 95 type and which takes air from the atmosphere and delivers it through a pipe 26 to the air intake 14 of the burner. As a simple means for operating the water and oil pumps, and the pressure blower, I may 100 mount them coaxially and drive all of them from a small electric motor 27 or other suitable source of power.

105 Although the invention, as illustrated, is particularly useful for boilers having low pressure steam such, for instance, as two (2) to ten (10) pounds, it would be obvious that it might be employed with higher pressure boilers. The blower is preferably a positive blower designed to give the re- 110

quired amount of air pressure for the vaporization of the oil and the distribution of the heat within the fire chamber. The oil pump is preferably such as will keep the 5 burner properly supplied and maintain a small oil pressure, for instance, about five (5) pounds in the pipe 22, the pressure relief valve 24 acting automatically to prevent a higher oil pressure and to permit 10 the excess to return to the tank.

In starting the apparatus the boiler may be initially heated in any suitable manner as, for instance, by building a fire of solid fuel in fire chamber 11 until the water is 15 raised to such a temperature that, when circulated through the heating coils of the tank, it will reduce the viscosity of the fuel and permit the free circulation of the latter. The circulating system may then 20 be started. The fuel burning at the burner 12 serves not only to generate steam in the boiler but a portion of the heat is utilized in keeping the liquid fuel in such condition that it may be freely and continuously de- 25 livered to the burner. It is important that water be taken from the boiler for this heating purpose and from a point below the water line rather than taking off steam which might tend to boil the fuel in the 30 tank 16 or evaporate the lighter fractions therefrom.

It will, of course, be obvious that under some atmospheric temperature conditions or with some liquid fuels the water circulating system need not be employed or may 35 be used only intermittently. I have shown the pipes 17 and 18 provided with shut-off valves 28 so that the circulation may be stopped whenever desired. The water pump 40 19 may be disconnected from the motor or the pump may be of such form that slip-

page or by-passing may occur when the valves 28 are closed.

Having thus described my invention what I claim as new and desire to secure by Letters Patent is:

1. In combination a steam boiler, a liquid fuel burner for heating same, a liquid fuel supply tank, means for delivering liquid fuel from said tank to said burner, and 50 means for circulating water from and to the boiler in heat interchanging relationship to said tank.

2. In combination a steam boiler, a liquid fuel burner for heating the same, a liquid 55 fuel tank having a heating coil, means for circulating water through said coil and boiler, and means for delivering liquid fuel from said tank to said burner.

3. In combination a boiler, a burner for 60 heating the same, a storage tank for viscous fuel, a heating coil in said tank, means including a pump for circulating water through said coil and said boiler, a liquid fuel circuit including a pump and supply 65 and delivery pipes connected thereto and to said tank, and means for delivering oil from said oil circuit to said burner.

4. In combination a low pressure steam boiler, a burner for heating the same, a supply tank for viscous fuel, means for delivering fuel from said tank to said burner, and means for reducing the viscosity of the fuel including a heating coil in the tank and connections including a pump between 75 said coil and said boiler below the water level of the latter.

Signed at New York city in the county of New York and State of New York this 5 day of March, A. D. 1920.

WILLIAM N. BEST.
